UNITED STATES PATENT OFFICE.

JULES ASCHEIM, OF NEW YORK, N. Y.

RIDING BOOT.

Application filed December 6, 1926. Serial No. 152,982.

This invention relates to footwear and has special reference to what is commonly known as a riding boot.

One object of the invention is to improve the general construction of upper for boots of this class.

A second object of the invention is to provide an improved boot of this class especially adapted for ease in putting on and removal from the foot of the wearer.

A third object of the invention is to provide an improved boot of this class having its upper arranged in two parts separably connected at their top portions in an improved manner.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of the improved boot showing the upper with its front and rear portions connected.

Figure 2 is a view similar to Figure 1 showing the upper with its front and rear portions disconnected.

Figure 3 is a section on the line 3-3 of Figure 1.

Figure 4 is a section on the line 4-4 of Figure 3.

In forming this boot there is provided the usual sole 10 and heel 11, the upper being secured as is ordinarily done on the sole. This upper consists of a front portion 12 made of a single piece of leather or the like and a rear portion 13 consisting of two halves stitched together at the back as indicated at 14. The lower parts of the forward edges of the rear portion and the rear edges of the front portion are united by stitching 15 which extends only a short distance up from the sole, the edges above the stitching being cut away to lie in spaced relation and provide a slit at each side reaching to the top of the upper. Both the front and rear portions are provided with linings indicated respectively at 16 and 17 and these linings are secured to the above mentioned edges and to the top of the shoe by stitching 18. Between the rear lining and the rear portion of the upper and also between the front lin-

ing and the front portion of the upper are strips 19 which are secured by the stitching 18 and these strips carrying interlocking elements 20 which may be close together or moved apart by a suitable cam device such as is shown at 21, the interlocking elements and cam forming the type of fastening that is well known as a "zipper". The rear lining has on each side a forwardly extending tongue portion 22 which is formed integral with the lining and overlaps the front portion of the upper on the inner side thereof. By this means the foot or sock is kept from contact with the fastening and the boot is given a smooth interior, this being aided by the fact that the free edges of the tongues are skived down to fit smoothly.

It will be noted that the slit extends to a point just above the forward edge of the heel and from a point midway of the front and back of the boot upper. Under these circumstances a boot is provided which is very easy to wear as there are no rough places or seams on the interior which tend to chafe the feet, and it will be obvious that the boot can be readily placed on the foot or removed since the entire forward portion of the upper separates freely from the rear portion of the boot and affords ample room for admitting the foot.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. A boot having an upper provided with front and rear portions separated from each other on opposite sides from the top of the upper to points adjacent the arch portion of the wearer's foot, means to detachably connect the respective front and rear edges, and a lining fitting within and secured to the rear portion of the upper and provided with tongue extensions overlapping the inner faces of the respective sides of the front portion of said upper.

2. A boot having a sole and a two part upper secured thereto, said upper comprising

front and rear portions stitched together for a short distance on each side from the bottom up and free from each other from the stitching to the top of the upper, the edges 5 of said front and rear portions above the stitching being in spaced relation to each other on respective sides of said upper, and strips carrying interlocking releasable fastening members secured to said edges to 10 close the space between the edges and to connect the front and rear portions of said upper.

3. A boot having a sole and a two part upper secured thereto, said upper comprising 15 front and rear portions stitched together for a short distance on each side from the bot-

tom up and free from each other from the stitching to the top of the upper, the edges of said front and rear portions above the stitching being in spaced relation to each other on respective sides of said upper, 20 strips carrying interlocking releasable fastening members secured to said edges to close the space between the edges and to connect the front and rear portions of said upper, 25 and a lining fitting within and secured to the rear portion of the upper and provided with tongue extensions overlapping the inner faces of the respective sides of the front portion of said upper.

In testimony whereof I affix my signature. 30
JULES ASCHEIM.
